Primary Examiner — Marie D. Fast Horse(74) *Attorney, Agent, or Firm* — Workman Nydegger(57) **CLAIM**

The ornamental design for a banknote processing machine, as shown and described.

DESCRIPTION

FIG. 1 is a perspective view of a banknote processing machine.

FIG. 2 is a front elevational view of the banknote processing machine of FIG. 1.

FIG. 3 is a first side elevational view of the banknote processing machine of FIG. 1.

FIG. 4 is a second side elevational view of the banknote processing machine of FIG. 1; and,

(Continued)

FIG. 5 is a top plan view of the banknote processing machine of FIG. 1.

The broken lines in the drawings depict portions of the banknote processing machine that form no part of the claim.
